DESIGN FOR AN ELECTRON DISCHARGE DEVICE

Harry R. Seelen, Short Hills, N. J., assignor to Radio Corporation of America, a corporation of Delaware

Application July 11, 1942, Serial No. 107,571

Term of patent 14 years

To all whom it may concern:

Be it known that I, Harry R. Seelen, a citizen of the United States, residing at Short Hills, in the county of Essex, State of New Jersey, have invented a new, original, and ornamental Design for an Electron Discharge Device, of which the following is a specification, reference being had to the accompanying drawing, forming a part thereof.

Figure 1 is a perspective view of an electron discharge device embodying my new design, and Figure 2 is a bottom view of the electron discharge device shown in Figure 1.

The opposite side of the electron discharge device is substantially the same as that shown in Fig. 1.

The characterizing features of my design for the electron discharge device shown reside in the specific narrow grooves in the shell as illustrated in Fig. 1 and in the disposition and arrangement of the parts on the bottom of the tube base as shown in Fig. 2.

I claim:

The ornamental design for an electron discharge device, substantially as shown and described.

HARRY R. SEELEN.
